BURT D. STEVENS, OF RIVERSIDE, AND MICHAEL A. DROITCOUR, OF CHICAGO, ILLINOIS, ASSIGNORS TO MIEHLE PRINTING PRESS & MANUFACTURING COMPANY, OF CHICAGO, ILLINOIS, A CORPORATION OF ILLINOIS.

SHEET-DELIVERY MECHANISM FOR PRINTING-PRESSES.

1,112,395.

Specification of Letters Patent. Patented Sept. 29, 1914.

Application filed October 18, 1911. Serial No. 655,442.

To all whom it may concern:

Be it known that we, BURT D. STEVENS, of Riverside, county of Cook, and State of Illinois, and MICHAEL A. DROITCOUR, of Chicago, in said county and State, have jointly invented certain new and useful Improvements in Sheet-Delivery Mechanisms for Printing-Presses, of which the following is a specification.

10 The principal object of this invention is the provision of a sheet delivery mechanism for printing presses the parts of which are so constructed and arranged that the device will deliver the sheets either printed side up or printed side down on the delivery pile with but very little manipulation in shifting from what may be characterized the main delivery mechanism to the fly delivery.

20 We propose to use for the main delivery what may be termed a mutilated endless conveyer, to which the sheets of paper are individually fed and carried over the pile, the construction being such that the conveying portion of the mutilated carrier passes out from beneath the paper after it arrives over the pile, so that the sheets drop individually onto the pile in proper position. The omitted part of the endless conveyer 25 permits the use of the fly delivery in place of the mechanism referred to, and under such circumstances the paper-carrying portion of the mutilated delivery device is temporarily housed or accommodated beneath the fly delivery mechanism. These, with other objects and advantages, will be made apparent from a consideration of the following detailed description of a plurality of embodiments of the invention which are 30 illustrated on the accompanying drawings forming a part of this specification, to which reference should be had for a complete comprehension of the invention.

40 In the drawings,—Figure 1 is a partial elevation and partial section of a printing press delivery mechanism embodying our invention; Fig. 2 is an enlarged section of the main delivery mechanism illustrating the manner in which it carries the sheets 45 over the delivery pile and drops them upon such pile; Fig. 3 shows the disposition of the parts of the mechanism just as a sheet of paper is being advanced thereto; Fig. 4 is a 50 plan view of the mechanism, the parts being

in the position indicated in Fig. 2; Fig. 5 55 is a vertical cross-section on line 5—5 of Fig. 4; Fig. 6 is an enlarged cross-section on line 6—6 of Fig. 2; Fig. 7 is a view similar to Fig. 2 illustrating another embodiment of the invention; Fig. 8 is a cross-section on line 8—8 of Fig. 9; Fig. 9 is a cross-section on line 9—9 of Fig. 7; and, Fig. 10 is a fragmentary cross-section showing the bar which causes the rotation of the rollers so constructed that it presses the sheets of 65 paper to the rollers.

By reference to the drawings, it will be observed that the frame 20 of the printing press at its delivery end is provided with a table 21 for the accommodation of the delivery pile of sheets. At and above each side of the table, the appliance is equipped with a suitably-supported endless sprocket-chain 22 of general horizontal disposition, which passes around two end sprocket-wheels 23 and 24, and also co-acts with an intermediate sprocket-wheel 25 and an idler-sprocket 26. Preferably, these pairs of sprocket-wheels are mounted on cross-shafts 27, 28, 29 and 30, the chains being driven in 70 any approved manner, but desirably by means of the rotation of the lower shaft 27 by a sprocket-chain 31 coöperating with a sprocket-wheel 32 on the end of shaft 27 and another sprocket-wheel 33 on a lower shaft 75 34, the latter being rotated by suitable driving means in any approved or desirable manner. Portions of the lengths of the chains 22, desirably but not necessarily approximately equal in length to the sheet of 80 paper to be delivered by the mechanism, are connected together transversely of the appliance by means of a plurality of parallel, hollow rollers 35, the opposite ends of each of which are equipped with an internal bearing member 36 apertured for the accommodation of the inwardly-protruding cylindrical journal end 37 of one of the rivets 38 which connects together and forms the pivotal joint for adjacent chain links 39 and 40, for example.

As is shown in Fig. 5, the bottom strands or stretches of the endless sprocket-chains 22 travel and rest on the top edges of a pair of supporting-bars 42, the inner ends 43 of 95 which are bent downwardly, as shown in Figs. 1 to 3, inclusive. The two sprocket-chains and the interposed rollers 35 consti-

tute what may be aptly characterized as a mutilated endless conveyer, to which the sheets of paper 44 are advanced by means of the customary endless tapes 45 passing around suitable pulleys or drums. Above one end portion of the rollers when they are above the delivery table 21, we mount, at one side of the machine, on a suitable support and by means of a pair of parallel links 46 and 47, an angle-friction bar 48 carrying on its under surface a facing 49 of leather or other suitable friction material, such leather, when the bar 48 is permitted to descend, contacting with the end portions 5 of the rollers 35 and acting to cause the rollers to rotate rearwardly as they travel forwardly with their supporting chains, the speed of rotation rearwardly being the same as that of their forward travel, so that a sheet of paper supported on such rollers, after it arrives over the delivery pile, remains stationary while the rollers pass out from beneath it, after which it falls by gravity upon the pile on the table 21. The advance or foremost roller 50 has on one end a sleeve or collar 41 adapted while beneath the bar 48 to hold the latter elevated sufficiently above the other rollers to prevent the engagement of its leather facing with such rollers. Consequently these rollers, with the exception of the first one, 50, do not begin to rotate on their own axis until after the roller 50 passes out from beneath the end of the friction bar 48, and when this occurs, the sheet of paper carried by the remaining rollers will be positioned above the delivery pile and will not travel farther; or, in other words, will remain substantially stationary, and will gradually descend, the rear end first, onto the delivery pile as the rollers escape from beneath it.

From the above description and the illustration referred to, it will be apparent that this mutilated endless conveyer makes a complete cycle of travel around the various sprocket wheels for the delivery of each sheet of paper, the direction of travel of the sprocket-chains and rollers being indicated by the arrows in Figs. 2 and 3. As soon as the roller 50 arrives under the inner end of the friction bar 48, as shown in Fig. 3, it lifts such bar sufficiently so that as the other rollers 35 come beneath the bar, the latter does not contact with their end portions. As we have shown in Fig. 3, the printed sheet of paper is fed forwardly on the tapes 45 so that its front end falls upon the roller 35 adjacent or just to the rear of the roller 50, and as the various succeeding rollers 60 come into horizontal alinement with those preceding them, the sheet of paper 44 is fed thereupon and conveyed by such roller forwardly over the delivery pile, as shown in Fig. 2. Just as it reaches this register with the pile on the table 21, the collar 41 on

roller 50 passes outwardly from beneath the bar 48, which then, by its own weight, descends so that its leather facing contacts with the end portions of the remaining rollers; then, as the chains and these rollers continue their travel, all of the rollers are revolved rearwardly at the same speed that they travel forwardly, whereby they pass out from beneath and without disturbing the position of the paper, which drops upon the pile. Then these various rollers pass back upon the top stretches of the chains, and by the time the roller 50 again reaches the position shown in Fig. 3, the next sheet 44 has been fed down by the tapes to be deposited upon the rollers 35 and delivered to the pile in the manner indicated.

On the shaft 30, the customary fly delivery sticks 51 are mounted, and the shaft is rocked for the fly delivery of the sheets by any approved mechanism, not illustrated. Obviously, the rollers 35 must not interfere with the sheets when delivered to the pile by the fly sticks 51, and in order to accomplish this, the sprocket 23 and its shaft 27 are placed below the fly mechanism and at a sufficient distance from the delivery pile so that all of the rollers may be accommodated beneath the fly delivery device when the latter is being actuated. Under these circumstances, the travel of the sprocket chains is interrupted so long as the fly mechanism is employed, whereby the sprocket-chains, having been once stopped with the rollers in position so as not to interfere with the actuation of the fly sticks, remain in such inoperative position until required for delivery on their own part.

In case the weight of the sheet of paper is not sufficient to cause adequate friction between the same and the rollers during the rotation of the latter in a backward direction, to prevent the sheet from traveling forwardly with such rollers, the bar 48 may be made of sufficient width, as shown in Fig. 10, to overlap a portion of the sheet of paper for the purpose of creating the friction referred to, or other suitable means may be employed for the same purpose.

In Figs. 7, 8 and 9, we have illustrated a suction device for frictionally holding the paper to the rollers during their backward rotation. The device in this case is practically the same as described above, but has in addition the suction means mentioned. This comprises a modification in the construction of the rollers themselves. In this embodiment, each roller is, in reality, a sleeve 60 provided with a considerable number of annularly arranged apertures 61 adapted during the rotation of the roller to be brought successively into register with corresponding apertures 62 through the top portion of a stationary, hollow drum 63 carried by the two stretches of sprocket-chains

and having its interior in communication, through the pivot pins of the chain-links with hollow connections 64 which travel above an elongated, hollow or chambered member 65 connected by means of a pipe 66 with a suction pump, not shown. This chambered member 65 has along its flat top a slot 67 with which the series of connections 64 are adapted to be brought into register during their travel above the delivery table. A belt 68 has its opposite ends fastened to bars 69 and 70 fixedly secured to and projecting laterally from the sprocket-chain 22, and this belt is apertured at 71, 15 in register with the holes in the connections 64 and in register with the slot 67. In this construction, during the rotation of the rollers upon their own axes, the sheet of paper 44 is held frictionally in contact with 20 the rollers or sleeves 60 by the suction applied thereto through the connections indicated, as follows: 61, 62, 63, 64, 71, 67, 65 and 66. The portions of the belt 68 which are not in register with the connections 64 25 are unapertured, so that as these sections of the belt 68 pass over the slot 67, they close such slot and prevent unnecessary leakage of air into the chambered member 65. When the slot 67 is not covered by any portion of 30 the belt, the suction connection therewith is automatically broken by a device of any suitable character, which it is not deemed necessary here to illustrate.

While we have herein indicated different 35 embodiments of this invention, we wish to have it understood that the invention is not limited and restricted to the precise and exact structural features described and shown, because these may be varied within 40 considerable limits without departure from the substance of the invention and without the sacrifice of any material benefits and advantages accruing from the invention.

We claim:

45 1. In a device of the character described, the combination of a pair of sprocket chains, sprocket wheels co-acting with said chains, a plurality of rollers between and carried by portions of the lengths of said chains and 50 adapted to transport the sheets of paper over the delivery pile, means to cause said chains to travel, means to feed sheets of

paper on top of said rollers while said rollers are on the bottom stretch of their travel, means to cause said rollers to rotate on their own axes after the paper has reached a position above the delivery pile to permit the rollers to travel from beneath the paper and permit the latter to fall on the pile, and means carried by the paper conveyer for controlling the action of said roller-rotating means, substantially as described.

2. In a device of the character described, the combination of a pair of endless sprocket chains, sprocket wheels co-acting with said chains, a plurality of rollers between and carried by portions of the length of said chains and adapted to support and transport the sheets of paper to the delivery pile, means to cause said chains to travel, means to feed sheets of paper on top of said rollers while the rollers are on the bottom stretch of their travel, a bar mounted to move toward and from the rollers and to contact therewith while the paper is above the delivery-pile to cause said rollers to rotate and pass from beneath the paper to permit the latter to fall on the delivery pile, and an enlargement on one of said rollers governing the contact of said bar with the companion rollers, substantially as described.

3. In a sheet delivery mechanism for printing presses, the combination of a fly delivery device, an endless conveyer delivery device, and an immovable support for the latter, the endless conveyer mechanism being adapted to assume a position on said immovable support in which it will not interfere with the operation of the fly device, substantially as described.

4. In a sheet delivery mechanism for printing presses, the combination of a fly delivery device, a mutilated endless conveyer delivery device, and fixedly mounted supporting wheels for the latter positioned and arranged to permit the sheet-conveying part of the conveyer to be housed beneath the fly device during the operation of the latter, substantially as described.
